UNITED STATES PATENT OFFICE.

ELWOOD BEBLER, OF LOS ANGELES, CALIFORNIA.

BOMB-PROJECTING GUN.

Application filed December 1, 1922. Serial No. 604,344.

To all whom it may concern:

Be it known that I, ELWOOD BEBLER, a citizen of the United States, residing at Los Angeles, in the county of Los Angeles and State of California, have invented certain new and useful Improvements in Bomb-Projecting Guns; and I do declare the following to be a full, clear, and exact description of the invention, such as will enable 10 others skilled in the art to which it appertains to make and use the same.

My invention relates to improvements in ordnance and the present disclosure is designed primarily for use upon bombing 15 planes for projecting the bombs or the like with force, whereby they will have greater velocity and can therefore be made to travel more accurately to the mark.

In carrying out the above end, an object 20 of the invention is to provide a single carrier for a plurality of projectile-discharging units, said carrier being movable to successfully present said units at a common point for operation.

25 A further object of the invention is to provide the projectile-discharging units with individual controls and to provide a relatively stationary master control for engagement with which said individual controls 30 may be successfully presented.

Yet another object is to make provision for easily retracting the master control from engagement with any of the individual controls, after operation thereof.

35 A still further aim of the invention is to provide a pair of operating handles for effecting movement of the carrier and operation of the master control, said handles being located adjacent each other, so that they 40 can be successively operated with ease.

A further object is to provide novel construction whereby each of the projectile-discharging units may be operated by compressed air.

45 With the foregoing and minor objects in view, the invention resides in the novel subject matter hereinafter described and claimed, the description being supplemented by the accompanying drawings.

50 Figure 1 is a side elevation of a gun constructed in accordance with my invention.

Figures 2 and 3 are vertical sectional views as indicated by lines 2-2 and 3-3 of Fig. 1.

55 Figure 4 is a central vertical longitudinal section, as indicated by line 4-4 of Fig. 2,

all parts being set in readiness for operation.

Figure 5 is a fragmentary longitudinal sectional view showing the position of parts 60 when a bomb or projectile is being discharged.

Figure 6 is a plan view partly in horizontal section, as indicated by line 6-6 of Fig. 5.

In the drawings above briefly described, the numeral 1 designates the carrier for the several projectile-discharging units, said carrier being here shown in the form of a cylindrical body rotatably mounted in appropriate bearing rings 2 and 3 which are connected in the present showing by a pair of parallel longitudinal bars 4 positioned over the carrier 1.

The projectile-discharging units are of a 75 pneumatic type in the form of construction herein disclosed and I prefer to employ the construction shown or an equivalent arrangement. The body 1 is provided with a plurality of circumferentially spaced bores 50 into whose front ends, suitable couplings 6 on the rear ends of barrels 7, are threaded, these barrels being adapted to receive the projectiles 8 and being provided with suitable spring-held detents 9 for holding said 55 projectiles in place. The couplings 6 are each provided with a valve seat 10 with which a suitable valve 11 co-operates to normally prevent escape of pressure from the bore 5 into the barrel 7. In the form of 90 construction shown, the valves 11 are provided with operating stems 12 with which cranks 13 on the inner ends of control shafts 14, are provided. These shafts are rotatably mounted in appropriate bearings carried by 95 the couplings 6 and are provided on their outer ends with gears 15 which constitute individual controls for the several projectile-discharging units adapted to be successively presented to another relatively stationary gear 16 which constitutes a master control.

The rear ends of the bores 5 are closed, for instance, by appropriate plugs 17 and I prefer to provide pistons 18 in said bores 105 which are held back against compression springs 19, by the air pressure, the several bores being provided with suitable charging valves 20 whereby air under pressure may be supplied thereto. It will be seen 110 that when the valve 11 is opened as seen in Fig. 5, the air pressure will escape and will

drive the projectile 8 from the barrel 7, during which movement, the spring-actuated piston 18 follows the air pressure and imparts a longer and more steady push to the projectile than would otherwise be transmitted thereto. Forward movement of the piston 18 is limited by a suitable internal stop 21 in the bore 5.

For turning the carrier 1 to successively present gears 15 to the gear 16, I have shown 10 a gear ring 22 surrounding said carrier and meshing with a pinion 23 which is loose upon a tubular shaft 24, this shaft being rotatable in a suitable bearing opening 15 formed in a bar 25 which connects the front ends of the bars 4. The rear end of the shaft 24 is provided with a handle 26 having a spring-pressed pin or the like 27 engageable with depressions 28 in the pinion 23 whereby a ratchet connection is established 20 between said handle and pinion for the purpose of rotating the latter to turn the carrier 1. The arrangement is such that the handle 26 swings between limits which are preferably defined by the bars 4, the movement of said handle between said limits, being sufficient to cause turning of the carrier 1 to such an extent as to move the projectile-discharging unit which has just 25 been fired, out of operative relation with the gear 16, thereby simultaneously presenting the next unit to said gear. This gear, in the form of construction disclosed, is provided with a shaft 30 rotatable in the tubular shaft 24. A handle 31 is pivoted at 32 to the rear end of the shaft 30, said handle being provided with an eccentric or cam 33 to abut the shaft 24 and shift the shaft 30 and gear 16 rearwardly when the handle 31 is moved to the position shown in Fig. 4. The gear 16 is thus disengaged from the gear 15 which it has just operated and it will be seen that when the next gear 15 is 40 presented, movement of the handle 31 into right angular relation with the shaft 30, will permit forward projection of this shaft, under the influence of a suitable spring 34, thereby intermeshing the two gears 16 and 15, as shown in Fig. 5. Thus, by turning 45 the handle 31, the gear 15 is turned to open the valve 11, permitting the escape of pressure which discharges the projectile. As soon as this has taken place, the handle 31 is moved to the position disclosed in Fig. 4, thereby disengaging the gear 16 from the gear 15 so that operation of the handle 26 may turn the carrier 5 to present the next projectile-discharging unit for operation by the master control means.

50 If desired, the muzzles of the several barrels 7 may be provided with longitudinal grooves 35 which tend to diminish the reports, caused by projection of the bomb or the like 8.

55 It will be seen that excellent results may

be obtained from the general association of parts shown and described. However, the present disclosure is for illustrative purposes only and it is to be understood that within the scope of the invention as claimed, 70 numerous minor changes may be made. Obviously, the gun may be attached to any desired style of aircraft, in any suitable manner, and when so attached, it will be seen that the several bombs will be steadily 75 held, so that they do not interfere with stabilization of the machine. It will be further understood that my invention is not restricted to use upon airships, but that it may be employed wherever desirable. 80

I claim:

1. A gun comprising a rotatably mounted carrier provided with longitudinally extended bores spaced circumferentially of the carrier, each bore being provided with a valve controlled fluid inlet, barrels extending from said bores and each provided with means for yieldably retaining a projectile in the barrels, control valves for the rear ends of said barrels each containing an actuating shaft extending externally of the barrel and a gear upon the outer end portion of the shaft, a rack extending circumferentially about said carrier, a tubular bearing shaft extending longitudinally of said carrier, a gear upon said bearing meshing with the teeth of said rack for imparting rotary movement to the carrier when the gear is rotated, a shaft slidably mounted in the bearing, a gear carried by said shaft for engagement by the gears of the control means for the valves of said barrels and moving the valves to an open position and returning them to a closed position during rotation of said carrier, and means for moving the shaft longitudinally to move the gear carried thereby into and out of position for engagement by the gears of the valve controlling means. 90

2. A gun comprising a rotatably mounted carrier having longitudinally extending bores therein and spaced circumferentially of the carrier, barrels extending from said bores, each bore being provided with an inlet for fluid under pressure, valves for controlling passage of the fluid into the barrels, control means for moving said valves into and out of a closed position and each including a rotatable shaft extending externally of its barrel and having a gear upon its outer end portion, a slidably mounted shaft, a gear carried by said slidably mounted shaft and when in an operative position adapted to be engaged by the gears of the valve actuating means to impart movement to the valve actuating means as said carrier is rotated to move the barrels successively into a discharging position, a spring yieldably holding said sliding shaft against longitudinal movement forcing the gear valve in an 110 115 120 125

operative position, means for moving said shaft longitudinally against the action of said spring to move the gear carried by said shaft out of an operative position, and 5 means for imparting rotary movement to said carrier.

3. A gun comprising a movable carrier having bores formed longitudinally therein, barrels extending from said bores, a 10 valve for the rear end portion of each valve, each valve being provided with actuating means including a shaft extending externally of the barrel and a gear upon said shaft, a rack carried by said carrier, a 15 loosely mounted gear engaging said rack for imparting movement to said carrier when rotated, means for imparting rotary movement to the last mentioned gear, a slidably mounted shaft extending longitudinally of 20 said carrier and yieldably held against sliding movement in one direction, a gear carried by the sliding shaft for engagement by the gears of the valve actuating means and cause opening and closing of the valves and 25 means for moving said sliding shaft longitudinally against the action of said spring

to move the gear carried thereby out of position for engagement by the gears of the valve actuating means.

4. A gun comprising a movable carrier 30 having longitudinally extending bores formed therein, barrels extending from said bores, a control valve mounted in the rear end portion of each barrel and each having actuating means including a shaft 35 extending externally of the barrel and provided with a gear upon its outer end portion, each bore being provided with an inlet in its forward end portion for fluid under pressure, plungers slidably mounted in said 40 bores and yieldably held against rearward sliding movement, means for limiting forward movement of said plungers, means for imparting movement to said carrier to successively move the barrels into a firing position, and means for engaging the gears of the valve control means of the bores to open and close the valves as the barrels pass the point of discharge.

In testimony whereof I have hereunto 50 affixed my signature.

ELWOOD BEBLER.
